FORCED FLOW STEAM GENERATING SYSTEM

Alfred Buri, Winterthur, Switzerland, assignor to Sulzer Freres, Societe Anonyme, Winterthur, Switzerland, a corporation of Switzerland

Application December 20, 1954, Serial No. 476,188

Claims priority, application Switzerland
December 24, 1953

6 Claims. (Cl. 122—33)

The present invention relates to a forced flow vapor generator provided with a conduit for diverting operating medium from the tube system of the vapor generator and a heat exchanger interposed in the aforementioned conduit for transferring heat from the diverted operating medium to the liquid operating medium flowing through the vapor generator. The system according to the invention is characterized by a flow control means for the operating medium in the aforementioned conduit downstream of the heat exchanger. This flow control means may be actuated in accordance with the pressure of the diverted operating medium while it flows through the heat exchanger. Alternatively, the flow control means may be actuated in accordance with the temperature of the operating medium at a suitable point in the tube system or at the outlet of the vapor generator.

The term "vapor" used in the present application includes steam. Where the word "steam" is used, this includes vapor of substances other than water. The term "water" used in the present specification includes any other operating medium in liquid state.

It has been proposed to divert operating medium from the tube system of a forced flow vapor generator for controlling the temperature of the superheated vapor leaving the vapor generator and to use the diverted operating medium for heating operating medium flowing in liquid state to or through the tube system of the generator. For this purpose a conduit is connected to the tube system of the vapor generator for conducting heating vapor through the primary side of a heat exchanger in which the heat content of the diverted operating medium is transferred to operating medium for the vapor generator in liquid state, and for returning the diverted operating medium after it has given up heat to the liquid operating medium, to the circuit of the operating medium of which the vapor generator forms a part. The flow of operating medium through the aforementioned conduit is controlled by a temperature-actuated valve disposed in the first part of the conduit. Since the diverted operating medium usually has a higher temperature than the temperature of bleeder steam which is used for feed water preheating in conventional steam turbine plants, the heat exchanger which is heated by operating medium diverted from the tube system of the vapor generator is preferably arranged downstream, with respect to the direction of flow of the feed water, of the last feed water heater which is heated by bleeder steam, so that advantage can be taken of the high temperature of the diverted operating medium without impairing the efficiency of the feed water heating system which receives heat from bleeder steam.

If the conduit receiving the diverted operating medium from the heat exchanger after the medium has released heat is connected to a part of the circuit of a power plant served by the vapor generator, for example to a feed water reservoir, the entire pressure drop occurs in the valve which is provided at the beginning of the conduit for diverting operating medium from the tube system

2

of the vapor generator. The pressure in the primary side of the heat exchanger is approximately the same as the pressure in the feed water reservoir. A temperature is coordinated to this pressure at which the operating medium condenses. If the temperature of the liquid operating medium in the feed water reservoir is higher than the aforementioned condensation temperature, the diverted operating medium does not condense, but flows in vapor state, without releasing heat of condensation, through the feed water reservoir and is blown into the condenser, if the pressure in the reservoir becomes too great. In this case, the heat content of the diverted operating medium is carried away by the condenser coolant and is wasted.

If a steam trap is interposed in the conduit for the diverted operating medium downstream of the heat exchanger, the pressure in the heat exchanger can be maintained sufficiently high, but only the condensate is removed, independently of the position of the valve at the inlet of the conduit for the diverted operating medium. This makes a satisfactory control impossible. If the pressure at the primary side of the heat exchanger is above the critical pressure, a steam trap is ineffective, because vapor and liquid have approximately the same density, and no liquid level can develop in the steam trap.

In contradistinction to the aforescribed conventional arrangements, the system according to the invention comprises a flow control means which is interposed in the conduit receiving operating medium from the heat exchanger after it has given up heat therein. This arrangement affords maintenance of a sufficiently high pressure in the heat exchanger as well as diversion of an amount of operating medium which affords a satisfactory control of the temperature of the operating medium leaving the vapor generator. The flow control means may be actuated in accordance with the pressure in the heat exchanger. For example, a predetermined pressure may be maintained in the heat exchanger. If the pressure rises, for example because the temperature-controlled valve at the inlet of the conduit for diverting operating medium opens wider, the flow control means downstream of the heat exchanger will also open wider, and either condensed or vaporized operating medium will be blown off. It is also possible to arrange a temperature-controlled valve at a point downstream of the heat exchanger, instead of at the beginning of the conduit for the diverted operating medium. In this case also, the pressure reduction will essentially occur downstream of the heat exchanger, so that a sufficiently high pressure and correspondingly high condensation temperature prevail in the heat exchanger.

The novel features which are considered characteristic of the invention are set forth with particularity in the appended claims. The invention itself however and additional objects and advantages thereof will best be understood from the following description of embodiments thereof when read in conjunction with the accompanying drawing, in which

Fig. 1 is a diagram of a steam power plant according to the invention;

Fig. 2 is a diagram of a modified part of the steam power plant illustrated in Fig. 1.

The same numerals designate the same parts in both figures.

A condensate pump 2 draws condensate from a condenser 1, and forces it through a conduit 3 into a reservoir 4 for liquid operating medium of the plant. A feed pump 5 pumps liquid operating medium from the reservoir 4 through a conduit 6 into a tube system including a primary heating surface 7 of a vapor generator 25. The operating medium which is preliminarily heated in the flue gas-heated heater or economizer 7 flows into the secondary or heat receiving side of a heat exchanger 8,

and therefrom into a second heating section 9 disposed in the combustion gas flow of the generator 25. The liquid operating medium is converted into vapor in the heating section 9, the vapor being conducted through a conduit 10 into a third combustion gas-heated heating section or superheater 11. The superheated operating medium flows through outlet means of the tube system into a main 12 and into a turbine 13 which drives an electric generator 14. The exhaust of the turbine 13 is conducted through a conduit 15 into the condenser 1.

For controlling the operation of the plant, a minor portion of the operating medium is diverted from the conduit 10 by means of a conduit 16 in which a flow control means or valve 18 is inserted. In the modification shown in Fig. 1, the valve 18 is actuated by means of a device 17 which is responsive to the temperature of the operating medium in the main conduit 12. The valve 18 is opened when the temperature in the steam main 12 falls, and vice versa. Downstream of the valve 18, the primary side of the heat exchanger 8 is interposed in the conduit 16 for receiving heating fluid from the conduit 16. After the operating medium supplied through the conduit 16 to the heat exchanger 8 has been cooled by releasing heat to the operating medium flowing from the heating section 7 of the vapor generator 25 to the heating section 9 of the generator, the operating medium flows through a valve 19 into the reservoir 4. The valve 19 is actuated by means of a device 20 which is responsive to the pressure of the operating medium upstream of the valve 19, which is the pressure prevailing in the primary side of the heat exchanger 8. The valve 19 is opened when the pressure in the primary side of the heat exchanger rises, and vice versa.

In the modification illustrated in Fig. 2, the temperature-controlled valve 18 in the conduit 16 upstream of the heat exchanger 8 is omitted, and the valve 19, which is designated by numeral 21 in Fig. 2, is actuated by the device 17 which is responsive to the temperature of the operating medium in the main conduit 12. The valve 21 is opened when the temperature in the steam main falls, and vice versa. Since the pressure of the operating medium upstream of the valve 21 and consequently also in the primary side of the heat exchanger 8 is approximately the same as the pressure of the operating medium in the vapor generator, the greatest possible amount of heating vapor is condensed in the heat exchanger 8, the condensate flowing through the valve 21 into the reservoir 4. At sufficiently wide opening of the valve 21, a part of the operating medium will not be condensed in the heat exchanger 8 and will arrive in the reservoir 4 in vapor state. If the pressure in the reservoir 4 becomes too great, vapor need not be blown off into the atmosphere, but is conducted through a conduit 22 into the condenser 1. The flow of vapor through the conduit 22 is controlled by means of a valve 23 which is actuated by a device 24 which is responsive to excessive pressures in the reservoir 4.

Many variations of the illustrated system may be made without departing from the scope of the present invention. The secondary side of the heat exchanger 8 may be arranged upstream instead of downstream of the heater or economizer 7. The temperature-responsive flow control means 18 may be arranged at a point of the tube system different from the one illustrated. The drawing is a diagrammatic showing only. An actual plant will have a great number of additional valves arranged in the conventional manner and will probably have conventional bleeder steam-heated preheaters for the liquid operating medium. The heating surfaces for the operating medium and/or the turbine 13 may be subdivided in various conventional ways.

What is claimed is:

1. A vapor generating system comprising a forced

flow vapor generator including a vapor generating tube system, outlet means from said vapor generating tube system adapted to conduct vapor to a consumer, a source of supply of relatively cold operating medium, a pump 5 interposed between said source of supply and said tube system for pumping operating medium from said source into and through said tube system to said outlet means, an indirect heat exchanger having a secondary or heat receiving side interposed in said tube system for flow 10 of operating medium through said heat exchanger, a first conduit connected with a relatively hot portion of said tube system downstream of said heat exchanger and upstream of said outlet means, said first conduit being connected with the primary or heat delivery side of 15 said heat exchanger for diverting a minor portion of the operating medium flowing through said tube system as a heating medium into said heat exchanger, a second conduit connecting the primary side of said heat exchanger with said source for returning the diverted operating medium to said source, and a flow control means 20 interposed in said second conduit for maintaining the pressure of the operating medium in the primary side of said heat exchanger above the pressure of the operating medium in said source.

25 2. A vapor generating system as defined in claim 1 in which said tube system includes an evaporating section and a superheating section and in which said first conduit is connected with said tube system between said evaporating section and said superheating section.

30 3. A vapor generating system as defined in claim 1 in which said tube system includes an economizer section and an evaporating section and in which said secondary side of said heat exchanger is interposed for operating medium flow between said economizer section 35 and said evaporating section.

4. A vapor generating system as defined in claim 1, including an actuating device connected with and responsive to the pressure of the operating medium in the primary side of said heat exchanger and being connected 40 with said flow control means for opening the latter when the pressure of the operating medium in the primary side of said heat exchanger rises, and vice versa.

5. A vapor generating system according to claim 4, including a flow control means interposed in said first conduit, and an actuating means connected with and responsive to the temperature of the operating medium leaving said tube system and being connected with said flow control means which is interposed in said first conduit for opening said last mentioned flow control means 50 when the temperature of the operating medium leaving said tube system falls, and vice versa.

6. A vapor generating system as defined in claim 1, including an actuating device connected with and responsive to the temperature of the operating medium leaving said tube system and being connected with said flow control means for opening the latter when the temperature of the operating medium leaving said tube system falls, and vice versa.
